UNITED STATES PATENT OFFICE

2,676,639

STRETCH-FORMING MACHINE

Landon R. Gray, Manhattan Beach, and Harry P. Smith, Jr., Los Angeles, Calif., assignors to Richard Seifried, Playa del Rey, Calif.

Original application September 2, 1950, Serial No. 182,928, now Patent No. 2,632,493, dated March 24, 1953. Divided and this application December 15, 1952, Serial No. 326,098

3 Claims. (Cl. 153—32)

1

This invention relates to a machine for forming bends in sheets while simultaneously stretching the sheets so that the same retain the bent form imparted by the machine. This application is a division of application Serial No. 182,928, filed September 2, 1950, issued March 24, 1953, as Patent No. 2,632,493.

A general object of the invention is to provide an improved stretch-forming machine that is particularly adapted to handle relatively large metal sheets with great efficacy.

Another object of the invention is to provide a machine of the character indicated that is more particularly adapted to stretch-form relatively wide sheets by forming them over a die of varying contour to impart more stretch to some parts of a sheet than to other parts, and to provide a novel arrangement of operating parts that enables forming a flat sheet to one that is wholly bent upon itself, i. e., with the opposite edges of the sheet parallel in their general planes.

A further object of the invention is to provide a machine, as indicated, having a fixed frame and swingable arms pivoted thereto and to so form said frame and arms that the stress forces resulting from application of power to stretch and form a sheet are substantially uniformly absorbed by said base and arms, the same resulting in improved accuracy of a stretch-forming operation.

A still further object of the invention is to provide, in a machine as indicated, novel, improved and powerful means to effect stretch-forming movement of the swingable arms, the same, at the same time, being extremely sensitive in its operation.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention which is given by way of illustration or example only.

In the drawings, like reference characters designate similar parts in the several views.

Fig. 1 is a plan view of a stretch-forming machine embodying the improvements of the present invention.

2

Fig. 2 is an enlarged front elevational view thereof showing the two sheet-bending arms in two different positions.

Fig. 3 is an end view as seen from the left of Fig. 2.

Fig. 4 is a plan sectional view on the plane of line 4—4 of Fig. 2, the same showing the left side of the machine, the right side being similar.

The machine that is illustrated comprises, generally, an elongated rigid base frame 5; an adjustable die box assembly 6 carried by said frame; a pair of swingable arm assemblies 7, one on each side of the base frame, a pair of hydraulic cylinder assemblies 8 connecting the base frame 5 and the free ends of each arm assembly to swing the latter between an aligned position and a position substantially parallel to said base frame; and a tension cylinder assembly 9 carried by each arm assembly and each having a sheet-gripping jaw 10, said jaws cooperating to hold a sheet 11 in position to be stretched and formed over a die 12 mounted on the die box assembly 6.

The base frame 5 may be variously made. As shown, the same comprises a fabricated structure of welded metal plates. Said base frame 5, as seen in Fig. 3, is generally C-shaped and comprises horizontally disposed base and cap portions 13 and 14, respectively, connected at their rearward ends by a vertical column 15 through the medium of transverse bolts 16. In this manner the base frame is provided with a front open space 17 in which die block assembly 6 resides. The C-shaped and elongated frame thus provided is rendered stable by laterally directed foot brackets 18 at the front and rear of base portion 13, the same affording means by which the frame may be bolted to a supporting surface.

Frame 5 is formed to have parallel sides 19 and, extending laterally from said sides, the base and cap portions 13 and 14 of the frame are each provided with bracket bearings 20, as best seen in Fig. 2. Said bearings are shown at the front of the frame and are arranged as opposed pairs above and below frame opening 17.

The upper face 21 of base portion 13 and the opposite under face 22 of cap portion 14 are each provided with a series of transverse and aligned key slots 23 that are utilized to locate die block assembly 24 relative to the open front of the frame. Said frame portions on each side, are each provided with bearings 24 for pivotal connection with one end of each of the hydraulic cylinder assemblies 8. Bearings 24 are provided intermediate the front and rear of said frame portions.

Die box assembly 6 is slidably fitted in space 17 between faces 21 and 22. The same comprises a box 25 on the front of which is affixed a vertical wall 26 on which die 12 is removably mounted. A platform 27 extends forward from the die box and serves as a support for spacers 28 on which the die rests. The thickness of said spacers varies according to the height and vertical disposition of the die in space 17. It will be understood that the die 12 is adjustably positioned in space 17 relative to the open end of the frame and is located and held as by means of keys 29 in a selected aligned pair of key slots 23. Said keys 29 may be projected into or retracted from said slots by means 30 which form no part of the present invention.

Each of the two arm assemblies 7 is formed as a generally C-shaped frame as best seen in Fig. 2. Each said assembly comprises upper and lower horizontally disposed arms 31 that are each provided with ears 32 arranged in pairs and connected to bearings 20 by pivot pins 33. In this manner, the arms 31 are generally horizontally aligned with the base and cap portions 13 and 14 of frame 5. Therefore, the space 34, defined between arms 31 of each arm assembly, is generally aligned with space 17 in the base frame. Also, in the present case, the upper face 35 of each lower arm is arranged to horizontally align with the upper face 21 of base portion 13, and under face 36 of each upper arm is similarly aligned with the under face 22 of cap portion 14. Key slots 37, comparable to key slots 23, are provided in faces 35 and 36.

The outer free ends of each pair of arms are each provided with a forwardly offset portion 38 and the same are connected by vertical members 39. To render rigid the portions 36 and member 39 of each arm, the latter, at its upper and lower end, is connected by a brace 40 to each respective arm 31 adjacent ears 32 of said arms. In this manner, each arm assembly 7 has a triangular form as seen in plan, and comprises a rigid C-shaped frame structure in which the vertical component 39 is forwardly offset providing a clear space in which tension cylinder assembly 9 is adapted to operate.

The vertical members 39 are each extended above and below the corresponding arms 31 and each said extension 41 mounts a pivot 42 for the outer ends of hydraulic cylinder assemblies 8.

Said assemblies 8 each comprises a cylinder 43 on pivot 24 and a piston in said cylinder and having a stem 44 connected to pivot 42. As will be seen, there are four such assemblies 8, two for each arm assembly 7, one above and one below the arms 31 of each of said arm assembly. Inasmuch as pivots 24 are on one side of pivots 33 and pivots 42 are on the opposite side, said cylinder assemblies 8 extend angularly relative to the general disposition of arm assemblies 7, i. e., said cylinder assemblies extend angularly across the arms 31 and particularly across the plane common to pivots 33 and the points of connection of tension cylinder assemblies and arm assemblies 7.

The cylinder assemblies 8 comprise extensible and contractable devices which, in this case, are hydraulically operated to provide power for swinging arm assemblies 7. It will be clear (see Fig. 4) without the need for detailed description that pressure fluid may be conducted to each cylinder 43, as at 45, to cause extension of stem 44 and at 46 to cause retraction of said stem, thereby changing the effective length of said as-

semblies. When said cylinder assemblies are extended, the arm assemblies 7 are outwardly extended on pivots 33. By contracting the cylinder assemblies, said arm assemblies can be swung rearward until they are disposed against and parallel to frame sides 19 and are parallel to each other, as shown by the dot-dash lines of Fig. 1. This position represents maximum retraction of the arm assemblies. Of course, any intermediate retracted position may be had, as illustrated in Fig. 4.

The details of the tension cylinder assemblies 9 are not important in this case, since the same are fully disclosed in the mentioned application of which this application is a division. Generally, each said tension cylinder assembly comprises a housing 47; a jaw-supporting tube 48 extending horizontally through said housing; a clevis 49 on that end of said tube that is directed toward the open end of the arm assembly mounting said tension cylinder assembly; transverse pivot 50 in said clevis; a sheet-gripping jaw 10 on said pivot and generally vertically disposed; means comprising two similar cylinder assemblies 52, also extending through housing 47, and responsive to greater resistance to movement of one end of the jaw than of the other, to stabilize said jaw on its pivot 50 and to hold said jaw in such stabilized position subsequent to any oscillation thereof on said pivot; a yoke 53 interconnecting assemblies 52 and tube 48 and disposed outward of housing 47; means comprising cylinder assemblies 54, out of yoke 53, interconnecting said tube and cylinder assemblies 52 and responsive to unequal forces on the jaw on opposite sides of pivot 49 that tend to rotate said jaw on the axis of the tube 48 to stabilize said jaw subsequent to any rotation thereof on said axis; and a pair of brackets 55 adjustable on and along arms 31 and pivotally mounting housing 47. The latter pivot is best shown at 56 in Fig. 4. Brackets 55 are held in adjusted position by keys 57 in a selected pair of aligned slots 37 of arms 31.

The cylinder assemblies 52 are operated by hydraulic fluid to retract or project tube 48 and jaw 10 thereon in the space 34. It will be clear, therefore, that a sheet 11, having its ends gripped by jaws 10 and spanning across the front of die 12, is adapted to be stretched by retraction of one or both tension cylinder assemblies 9 as above generally described, and that said jaws are free to pivot with said assemblies 9 on pivots 56 during swinging of the arm assemblies as also described above. Such pivotal movement of assemblies 9 may be effected and controlled by means of a cylinder piston unit 58 extending between each lower bracket 55 and an extension 59 on each housing 47.

It will be seen from the foregoing that the stretch-forming machine provided comprises three C-shaped frames of which one is fixed and the other two are swingable relative thereto; that said three frames are so arranged relatively that the openings or spaces between their horizontal arms combine to create a clear space in which the tension cylinder assemblies 9, the die 12, and the sheet 11 that is formed around said die, are disposed; that the die is effectively supported by the arms of the fixed frame which receive the forces imparted to the die during the machine operation; and that the arms of the swinging frames serve in a similar capacity to take the forces generated in the tension cylinder assemblies. Therefore, the present machine is quite stable, well-balanced, and resistant to distortion

by the stresses resulting from the forces generated.

While we have illustrated and described what we now contemplate to be the best mode of carrying out our invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described our invention, what we claim and desire to secure by Letters Patent is:

1. A stretch-forming machine comprising a C-shaped base frame having upper and lower horizontal frame portions connected at the rear by a vertical portion to define a front-open space, horizontally adjustable means disposed in said space and adapted to mount a forwardly-facing die, a pair of bearing brackets carried by the forward end of each horizontal frame portion, said pairs of brackets being arranged as opposed and aligned pairs on each side of the base frame, one above and one below said frame opening, a generally C-shaped arm on each side of the base frame and comprising upper and lower horizontal portions and an end vertical portion connecting the horizontal portions at their ends and laterally offset from the general plane of said arm, pivots on the other ends of the arms connecting each said arm to the mentioned opposed and aligned pairs of bearing brackets, respectively, the mentioned offset vertical portion of said arms, when said arms are aligned with each other on the mentioned pivots and extend in opposite directions from the base frame, being disposed forwardly of the open front of the base frame, two vertically aligned pairs of pivots in the horizontal portions of the base frame intermediate the forward open end of said frame and the rear vertical portion thereof, and a pair of upper and lower extensible and contractable devices extending in extensible condition from each pair of vertically aligned pivots in the intermediate portion of the base frame diagonally across each respective arm and pivotally connected to the vertical offset portion of each respective arm, said extensible and contractable devices being, thereby, disposed at a forward and outward angle when the arms are aligned and oppositely directed, said devices being fluid operated to contract and move the arms on their respective pairs of pivots from the mentioned aligned position to a position substantially parallel to the sides of the base frame and to each other and wherein the offset vertical portions of the arms are in opposed relation to each other, the contracted devices, in the latter position of the arms, extending from their pivots in the base frame at a rearward and outward angle diagonal-

ly across the substantially parallel arms, each arm mounting sheet-gripping and -tensioning means movable with the arms to bend a sheet spanning between the latter means around said die during movement of the arms from their aligned position toward their parallel position.

5 2. A stretch-forming machine according to claim 1 the end of each arm opposite the aligned pair of pivots thereof being open, and the sheet-gripping and -tensioning means extending, in part, through said opening and beyond the outer end of the arm.

10 3. A stretch-forming machine comprising a base provided with horizontal adjustable means 15 mounting a forwardly facing die, the forward end of said base being provided with laterally directed bearing brackets, one on each side of the base, an arm pivotally connected by one end to each bearing bracket and each arm being provided with an offset portion at the opposite end thereof, said portions being offset forwardly of the forward end of the base when said arms are 20 aligned on their pivots with each other and substantially at right angles to the base, a pair of pivots provided in the base intermediate the front and rear thereof, an extensible and contractable device extending from each of said pair of pivots diagonally across each respective arm and pivotally connected to the offset portion of each said 25 respective arm, said devices, thereby, extending at a forward and outward angle with respect to the base when said arms are aligned as mentioned, said devices being in extended condition 30 in the latter position of the arms, said devices being fluid operated to contract and move the arms on their respective pivots from the mentioned aligned position to a position substantially parallel to the sides of the base and to each other and wherein the offset portions of the arms are 35 in opposed relation to each other, the contracted devices, in the latter position of the arms, extending from their pivots in the base at a rearward and outward angle diagonally across the 40 substantially parallel arms, each arm mounting a sheet-gripping and -tensioning means movable with the arms, to bend a sheet spanning between the latter means around said die during movement of the arms from their aligned position toward their parallel position.
